(57) **CLAIM**

The ornamental design for a section of prying bar, as shown and described.

DESCRIPTION

FIG. 1 is a front elevation view of a section of prying bar showing my new design;

FIG. 2 is a back elevation view thereof;

FIG. 3 is a top plan view thereof;

FIG. 4 is a bottom plan view thereof;

FIG. 5 is a right side elevation view thereof; and,

FIG. 6 is a left side elevation view thereof.

The broken line disclosure at the ends of the section of prying bar shown in FIGS. 1–6 define the boundaries of the claimed subject matter, but form no part of it.
